CONCRETE TREATING AND FINISHING
MACHINEJohn W. Poulter, Wauwatosa, Wis., assignor to
Koehring Company, Milwaukee, Wis., a corpora-
tion

Application May 7, 1941, Serial No. 392,376

15 Claims. (Cl. 94—45)

This invention relates to a method and apparatus for finishing concrete pavements, and more particularly to novel improvements in such apparatus and method.

In the art of laying concrete roads, the customary practice is to traverse the concrete deposited on the road bed by the mixing machine with a finishing machine adapted to compact the concrete and finish the surface of the same. The purpose of such machines with respect to compacting has been to bring to the surface of the concrete excess-water and entrapped air. To secure the compaction action a variety of devices has been developed including the common reciprocating screed and various vibrating and tamping devices.

The common screed may have some compacting effect, but by reason of the fact that its movement is only lateral with respect to a single point on the upper area of the concrete, a uniform working or compacting movement of the concrete is not effected, since such devices fail to impart movement to all parts of the concrete tending to compact the same. With the present tendency of using so-called dry mixes resulting in a stiffer or less plastic concrete, the disadvantage of the present methods and apparatus used for finishing the concrete becomes more pronounced.

Likewise, vibrating and tamping devices fail to give a uniform working of the complete mass of concrete being treated. Tamping devices tend to create high pressure areas with a tendency to key the larger aggregate in the same position as it was when the pressure was applied, while a vibrating device employing only one frequency may have a consolidating effect on one size or weight of particles, and a fluffing or loosening effect on another size. In both cases there is a rapid decrease in the effect, as the distance from the point of contact with the concrete increases.

In compacting concrete, it is desirable to move the aggregate or coarse pieces of stone or gravel as close together as possible, leaving a minimum amount of space between such pieces, which is filled by the grout or cement paste employed as a binder for the coarse particles of aggregate. It is recognized that a general uniform working of the entire mass of concrete will cause the desired movement of the coarse pieces of aggregate into a close overlap relationship. As indicated earlier, a uniform movement of the complete mass of concrete is not caused by either the common screed or vibrating mechanism and with tamping, there is the tendency to key the particles in the same position they occupied at the

initial application of the tamping action. Moreover, the force is definitely not uniformly distributed throughout the mass.

The principal object of this invention has been to devise a novel method of working concrete by which the individual particles of aggregate will be moved into a uniform dense compact arrangement or position with each other forming a concrete with uniform density throughout the complete mass. The method comprises the application of force or pressure to the surface of a narrow strip of concrete at spaced points and causes the points of application of such force to continually move back and forth across the strip in the form of a wave motion whereby the concrete will be uniformly moved or worked into a dense compact mass.

The invention also contemplates the provision of apparatus for carrying out the method in which a working device having a wave-like surface is engageable with the surface of the concrete to be compacted. Means are provided to cause movement of the high and low points on the wave-like surface of the working device across the concrete in an undulating manner for causing the desired compacting movement of the concrete.

In the drawings, I have illustrated a form of apparatus by which the principles of this invention may be carried out. In this showing:

Figure 1 is a plan view of a machine constructed in accordance with the principles of the invention.

Figure 2 is a side elevational view of the machine shown in Figure 1.

Figure 3 is an end view of the machine shown in Figure 1, parts thereof being broken away.

Figure 4 is a view showing one of the concrete working devices carried by the machine shown in Figure 1, and illustrating its manner of application to concrete which has been deposited between suitable forms on a road bed.

Figure 5 is a sectional view taken substantially along the line 5—5 of Figure 4.

Figure 6 is a view similar to Figure 4 illustrating another form of concrete compacting device and its manner of application.

Figure 7 is an enlarged view of the compacting device shown in Figure 6, parts thereof being broken away to illustrate its construction.

Figure 8 is a sectional view taken substantially along the line 8—8 of Figure 7.

Figure 9 is a view diagrammatically illustrating the relative positions of the eccentric drives shown in the device illustrated in Figure 7.

Figure 10 is a view further illustrating the manner of application of the concrete working device shown in Figure 6; and,

Figure 11 is a view illustrating the combined use of the concrete working devices shown in Figures 4 and 6.

Referring to Figures 1, 2 and 3 showing a concrete finishing machine, the numeral 1 indicates the frame work of the machine which is movably supported by flanged wheels 2 mounted on an axle 3 rotatably secured by bearings 4 to the frame 1. The flange wheels 2 are adapted to ride on steel forms 5 between which the concrete 6 is poured on the surface of the road bed 7. A motor 8 is mounted on the frame 1 and through a suitable drive such as the belt 9 is adapted to cause forward movement of the machine over the surface of the road. The motor 8 is also adapted to actuate concrete finishing devices or screeds 10 and 11, the construction of which will be presently described, for effecting a compacting action of the concrete.

The screed 10 comprises a transverse vertical plate 12, side members 13 and a flexible bottom member 14. A drive shaft 15 is rotatably mounted on the side members 13 and is adapted to be driven from the motor 8 in a manner which will become apparent. A plurality of eccentrics 16 are keyed to the shaft 15 for imparting vertical movement to the connecting rods 17 which are connected by wrist pins 18 to connecting members 19 secured to the flexible bottom member 14 of the screed 10. By this arrangement, the flexible member 14 is supported from the shaft 15. Adjustable devices 19' are provided for changing the lengths of the arms 17 in order to adjust the position of the flexible member 14 to allow for the crown of the road.

As best shown in Figure 4, the eccentrics 16 are mounted 180° apart to provide a series of alternate high points 20 and low points 21 on the actuating surface of the flexible member 14 for a purpose which will become apparent.

A generator 22 is mounted on the frame 1 and is driven from the drive shaft 23 by a pulley belt 24. The electric current generated by the generator 22 is used to drive a motor 25 mounted on the screed 10. The motor 25 operates a shaft 26 which in turn is operative to rotate the shaft 15 through a suitable worm gear drive (not shown).

Accordingly, it will be apparent that when the motor 25 is operated to rotate the shaft 15, the high and low points 20 and 21 on the flexible member 14 will be moved vertically in reverse directions by the eccentrics 16 mounted on the shaft 15. By reason of the fact that the member 14 extends transversely of the road bed, the force exerted by the eccentrics 16 will be distributed over the surface of the concrete in various directions to not only present vertical forces to the surface of the concrete, but also forces tending to move the concrete in the direction of the arrows shown in Figure 4 for imparting a kneading action to the concrete.

The screed 10 is adapted to be reciprocated transversely with respect to the forms 5 and, to this end, a pair of inverted channel-shaped members 27 slidably supported by members 28 are provided. Each of the members 28 is pivotally connected to a link 29 which has one end thereof connected pivotally to a supporting member 30 secured to the frame 1. The other end of the link 29 is pivotally connected to a vertically movable rod 31 which is adapted to be moved verti-

cally by means of a manually operable hand wheel 32 which has a threaded connection with the rod 31.

The vertical position of the screed 10 may be adjusted through proper manipulation of the hand wheels 32. The arrangement of the parts permitting vertical adjustment and lateral movement of the screed 10 is well known in the art and forms no part of this invention.

10 A shaft 33 is rotatably driven from a transmission 34 controlled by a lever 35 and mounted on the frame 1, the transmission 34 being driven from the motor 8 by the shaft 23. An eccentric 36 is keyed to the shaft 33 for imparting reciprocating movement to the connecting rod 37 which is pivotally connected to one end of a rocker arm 38. The rocker arm 38 is pivotally connected to the frame 1 by a pin 39 and has its other end provided with a vertical slot 40 for engagement with an actuating member 41. As best shown in Figure 5, the actuating member 41 is connected to the transverse plate 12 for imparting transverse movement to the screed 10 upon operation of the shaft 33 to impart a rocking movement to the rocker arm 38.

With the motor 25 driving the eccentrics 16, it will be apparent that the transverse reciprocating movement of the screed by the rocker arm 38 will constantly change the position of the eccentrics 16 and the alternate high and low points 20 and 21 on the flexible member 14 with respect to the surface of the road. A combined vertical and horizontal movement is thereby imparted to the high and low points 21 and 20 whereby each 35 part of the transverse strip of concrete being operated on by the screed 10 will be uniformly subjected to a constantly changing pressure in an integrated manner.

It will be appreciated that Figure 4 exaggerates 40 the amount of throw of the eccentrics 16. It is desirable that the shaft 15 be driven at a high rate of speed and that the throw of the eccentrics 16 be made only a small fraction of an inch. However, the amount of throw the eccentrics 16 45 and the speed of rotation of the shaft 15 may be adjusted as the circumstances require by rotating the devices 19' so that the threaded portions thereof will cause raising or lowering of the members 19 with respect to the eccentric shaft 15.

50 A supporting member 42 is spaced above the tail portion 43 of the flexible member 14 and has opposite ends thereof suitably secured to opposite side members 13 of the screed 10. The member 42 in addition to serving as a support for the 55 motor 25 carries adjustable members 44a by which the tail end portion 43 of the flexible member 14 may be adjusted for the crown of the road.

The vertical position of the member 42 with 60 respect to the road is controlled by the hand wheels 32. The adjustable members 44a are connected to the member 42 and the tail portion 43 in order that the position of the tail portion 43 65 may be adjusted with respect to the member 42. Since the particular means for causing the screed 10 to conform to the crown of the road forms no part of this invention, the connections of the adjustable members 44a to the member 42 and to the tail portion 43 are not illustrated in detail.

65 Referring to Figure 1, it will be noted that the screed 11 is formed of two identical sections 44 and 45. The construction of each of the sections 44 and 45 is best shown in Figures 6, 7 and 8, and 70 each section comprises a plurality of rollers 46

rotatably mounted on a shaft 47, there being similar shafts 47 for each of the sections 44 and 45. Each of the rollers 46 comprises a hollow cylindrical element having an integral annular member 48 formed adjacent one end thereof. The rollers 46 and the integral annular members 48 are rotatably supported with respect to the shaft 47 by a roller bearing assembly 49 comprising an outer race 50 keyed to the annular member 48 and an inner race 51 keyed to an eccentric 52 which is in turn keyed to the shaft 47. Roller bearings are positioned between the races 50 and 51, and it will be noted that the inner surface of the race 50 is curved to provide a roller bearing assembly of the self centering type to permit angular movement of the rollers 46 with respect to the shaft 47.

As best shown in Figure 7, it will be noted that an end 53 of each roller 46 is mounted in overlapping relationship with respect to the annular portion 48 of an adjacent roller 46 in order that each of the sections 44 and 45 will present a substantially continuous surface to the surface of the concrete for a purpose which will become apparent.

A flexible rubber member 54 is mounted on the annular member 48 and acts as a filler for the space between the ends 53 and the outer surface of the next adjacent roller 46 to permit angular movement of the rollers 46 with respect to each other without breaking the continuity of the surfaces of the sections 44 and 45.

Each of the shafts 47 is provided with supporting members 55 concentrically mounted for rotation with respect thereto and at the outer ends thereof. The edge 53 of each roller 46 adjacent the supporting member 55 extends in overlapping relationship with respect to the member 55 in the same manner as heretofore described for the edges 53 with respect to adjacent rollers 46. The supporting members 55 are adapted to roll along the surface of the forms 5 between which the concrete has been deposited.

The inner end of each shaft 47 is rotatably carried by supporting members 56 which are similar in construction to the supporting members 55.

The members 56 are connected to a vertically movable element 57 as shown in Figures 1 and 2 for vertical movement thereof with respect to the surface of the road in order that each of the sections 44 and 45 may be given an adjustment for the crown of the road. The member 57 is carried by a member 58 extending longitudinally of the sections 44 and 45.

The outer ends of the shafts 47 are rotatably mounted in brackets 59 which are respectively pivotally connected to a drive shaft 60 extending transversely of and rotatably connected to the frame 1. The brackets 59 space the screed 11 from the frame 1 and permit vertical adjustment of the screed 11 with respect to the frame 1. To provide for adjustment of the screed 11, adjustable members 61 are pivotally connected at 62 to the outer edges of the member 58, the member 58 being provided with side members 63 fastened as by rivets 64 to the brackets 59. The member 61 has the other end 65 thereof threaded for engagement with an internally threaded hand wheel 66, rotation of which will thereby effect movement of the members 61, 58 and 59 for adjusting the position of the screed 11 vertically with respect to the road.

A pulley 67 is keyed to the shaft 60 and is driven by a belt 68 from a pulley 69 keyed to the shaft 75

23. Pulleys 70 are keyed to the outer ends of the shaft 68 and have belts 71 reeved with respect thereto for driving pulleys 72 keyed to the outer ends of each of the shafts 47.

5 It will be apparent that the arrangement of the pulleys 70 and 71 provide a separate drive for each of the shafts 47.

In Figure 9, the position of the eccentrics 52 with respect to each other on the shaft 47 is 10 diagrammatically illustrated. The eccentrics are shown as occupying a position of angular advancement of 45° with respect to each other along the shaft 47. By this arrangement every fourth roller will provide a high point along the surface 15 of the sections 44 and 45 and every eighth roller will provide a low point. On movement of the shaft 47 through an angle of 45°, the respective high and low points on the sections 44 and 45 will be shifted to the next succeeding roller.

20 In operation, the shaft 47 will be driven at a high rate of speed and the throw of the eccentrics or cams 52 will be only a small fraction of an inch. In Figure 6, the wave-like surface which will be presented to the surface of the concrete is illustrated and it will be appreciated that the position 25 of the high and low points with respect to each other has been exaggerated for the purposes of illustration. Obviously, the number of rollers employed in each of the sections 44 and 45 and the 30 position of angular advancement of the eccentrics 52 with respect to each other along the shaft 47 may be varied as the circumstances require.

From the above, it will be apparent that when 35 the shafts 47 are rotated the high and low points presented by the wave-like surface of the rollers 46 to the surface of the concrete will be progressively shifted with respect to the surface of the concrete in an integrated manner and the wave-like surface of the rollers 46 will be moved over 40 the surface of the concrete in an undulating manner. Accordingly, it will be apparent that the strip of concrete immediately underneath the rollers 46 will be subjected to a series of high and 45 low points or vertical forces which will be constantly and progressively moving over the strip of the concrete whereby a uniform working and compaction of all the concrete under the sections 44 and 45 will be effected.

The supporting member 58 is provided with a 50 plate member 73 extending longitudinally of the sections 44 and 45 and angularly toward the surface of the rollers 46. The plate member is fastened to each of the side members 63 and together with such members forms a hopper-like 55 construction for carrying the excess concrete in front of the rollers 46 as best shown in Figures 10 and 11. A hard rubber scraping member 74 having sufficient resiliency to follow the variations in the surface presented by the rollers 46 is secured to the bottom edge of the member 73 60 for engagement with the surfaces of the rollers 46.

In operation, the flange wheels 2 carrying the 65 frame 1 will be mounted on the forms 5 between which the concrete to be compacted by the screeds 10 and 11 has been deposited. Upon starting of the motor 8, the screed 10 will be reciprocated transversely of the forms 5 by the rocker arm 38 in the manner heretofore described. At the same time the generator 22 will supply current to the motor 25 to rotate the shaft 15 and operate the eccentrics 16 for alternately reversing the positions of the high and 70 low points 20 and 21 along the surface of the flexible member 14.

With the screed 10 operating in the manner just described, the shaft 23 through the belt 68 will cause rotation of the shaft 60 for driving the shafts 47 of the respective sections 44 and 45 of the screed 11. Rotation of the shafts 47 will cause movement of the high and low points presented by the surfaces of the rollers 46 with respect to the concrete across the surface of the concrete. The eccentrics or cams 52 being keyed to the shafts 47 and rotatable relevant to the rollers 46 will cause the relative positions of the eccentrics 52 with respect to the rollers 46 to be changed and cause movement of the surfaces of the sections 44 and 45 in an undulating manner.

At the same time, the drive 9 will cause forward movement of the screeds 10 and 11 with respect to the concrete, the rate of forward speed being dependent upon the speed ratio provided by the drive 9. Forward movement of the frame 1 will cause the screed 10 to be dragged over the surface of the concrete and cause the rollers 46 to roll over the surface of the concrete.

Figure 11 illustrates diagrammatically the manner in which the two different types of screeds 10 and 11 will operate together on a single strip of concrete. However, it will be appreciated that this arrangement may be varied as the circumstances require by eliminating one of the types of screeds shown in Figures 5 and 10. From the foregoing, it will be apparent that the screeds 10 and 11 illustrate a novel method of working and compacting concrete. By their use, a strip of concrete may be subjected to a continuous vertical pressure at points spaced from each other and the points of application of vertical pressure will move progressively back and forth across the strip of concrete. In addition, such forces are applied to the concrete by a member which provides a substantially continuous surface in engagement with the concrete whereby component forces will be applied to the concrete at points intermediate the points of application of the vertical forces. Accordingly, it will be recognized that the foregoing is a substantial improvement over the prior art, wherein it has been customary to apply a reciprocating force to a single point of area of concrete.

Having thus described my invention, what I claim as new and desire to secure by Letters Patent of the United States, is:

1. The method of working concrete which consists in the application of a substantially continuous working surface having a plurality of spaced apart high and low points to a strip of concrete, subjecting said working surface to vertical forces at spaced apart points to alternately reverse the positions of said high and low points, and applying the vertical forces progressively with respect to the strip of concrete whereby to subject all parts of said surface at times to said forces in an integrated manner for effecting a compacting movement of the concrete under said working surface.

2. In apparatus of the character described, means for working concrete comprising a device having a substantially continuous surface engageable with the surface of a strip of concrete and provided with a plurality of spaced high and low points thereon, and means for actuating said device to alternately reverse the positions of said high and low points for effecting a compacting movement of the concrete under said device.

3. In apparatus of the character described, means for working concrete comprising a device having a substantially continuous surface en-

gageable with the surface of a strip of concrete and provided with a plurality of spaced high and low points thereon, and means for actuating said device to cause movement of said points across the surface of the concrete progressively in an undulating manner for effecting a compacting movement of the concrete under said device.

4. In apparatus of the character described, 10 means for working concrete comprising a device having a substantially continuous surface engageable with the surface of a strip of concrete and provided with a plurality of spaced high and low points thereon, means for actuating said device to alternately reverse the positions of said high and low points, and means for moving said device with respect to the strip of concrete to subject all parts of the strip to said high and low points in an integrated manner for effecting a uniform compacting movement of the concrete under said device.

5. In a concrete compacting machine, in combination, a movable support adapted to be advanced over the surface of the concrete to be compacted, a screed carried by said support and provided with a substantially continuous wave-like surface engageable with the surface of the concrete, said wave-like surface presenting a series of alternately located high and low points to the surface of the concrete, and means for reversing the position of said high and low points for effecting a compacting action of the concrete.

6. In a concrete compacting machine, in combination, a movable support adapted to be advanced over the surface of the concrete to be compacted, a screed carried by said support and provided with a substantially continuous wave-like surface engageable with the surface of the concrete, said wave-like surface presenting a series of alternately located high and low points to the surface of the concrete, means for reversing the vertical position of said high and low points for effecting a compacting action of the concrete, and means for reciprocating the screed laterally with respect to the line of advancement of said screed.

7. In a concrete compacting machine, in combination, a movable support adapted to be advanced over the surface of the concrete to be compacted, a screed carried by said support and provided with a substantially continuous wave-like surface engageable with the surface of the concrete, said wave-like surface presenting a series of alternately located high and low points to the surface of the concrete, means for reciprocating the said wave-like surface in contact with said concrete surface for reversing the position of said high and low points for effecting a compacting action of the concrete, and means including eccentric drive parts operatively connected with said screed to impart up and down movements in reverse directions to said high and low points for effecting a compacting action of the concrete.

8. In a concrete compacting machine, in combination, a movable support adapted to be advanced over the surface of the concrete to be compacted, a screed carried by said support and engageable with the surface of the concrete, a plurality of eccentric driving parts operatively connected to said screed at spaced points occupying a position of angular advance with respect to each other of substantially less than 180°, and drive means for said eccentric parts to cause

movement of said screed in an undulating manner for effecting a compacting action of the concrete under said screed.

9. In a concrete compacting machine, in combination, a movable support adapted to be advanced over the surface of the concrete to be compacted, a flexible screed carried by said support and engageable with the surface of the concrete, a plurality of eccentric driving parts operatively connected to said screed at spaced points and occupying a position of angular advance with respect to each other of substantially 180°, and drive means for said eccentric parts to cause flexing movement of said screed in an undulating manner for effecting a compacting action of the concrete under said screed.

10. A machine as claimed in claim 9, combined with means for reciprocating said screed laterally with respect to the line of advance of said support.

11. In a concrete compacting machine, in combination, a movable support, a drive shaft rotatably mounted on said support, a plurality of rollers rotatably mounted on said drive shaft, an eccentric drive for each of said rollers, secured to said shaft and occupying a position of angular advance along said shaft with respect to each other of substantially less than 180°, means securing each of said rollers to an adjacent roller whereby a wave-like surface will be presented thereby to the surface of the concrete to be compacted, and means for rotating said shaft to cause movement of said rollers through said eccentric drives in an undulating manner relative to said shaft for effecting a compacting action of the concrete under said rollers.

12. In a concrete compacting machine, in combination, a movable support, a drive shaft rotatably mounted on said support, a plurality of eccentric drive members secured to said shaft at spaced points and occupying a position of angular advance with respect to each other of substantially less than 180°, a cylindrical roller rotatably secured to each of said drive members at

points adjacent one end thereof, each of said rollers having its opposite end movably connected to an adjacent roller whereby a wave-like surface will be presented by said rollers to the surface of the concrete to be compacted, and means for rotating said shaft to cause movement of said rollers through said eccentric drives in an undulating manner relative to said shaft for effecting a compacting action of the concrete under said rollers.

13. The method of finishing a slab of concrete, which includes applying a continuous working surface to the surface of the concrete aggregates, alternately applying to the surface thereof a plurality of vertical forces while the working surface is maintained in contact with said aggregates, reciprocating said working surface in a transverse direction, and moving said working surface longitudinally of said slab while continuing application of the aforesaid vertical forces and movement of the working surface in a transverse direction.

14. The method of compacting a slab of concrete, which comprises applying a continuous flexible working member to the surface of a strip of said slab, alternately actuating successive portions of said member by a plurality of vertical forces throughout the length of said member, and bodily moving the member at an angle to the length thereof while said working member is in contact with the surface of the slab being compacted.

15. The method of compacting a slab of concrete, which comprises applying a continuous flexible rolling working member to the surface of a strip of said slab, alternately actuating successive portions of said member by a plurality of vertical forces throughout the length of said member, and bodily moving the member at an angle to the length thereof, while said rolling working member is in contact with the surface of the slab to effect rolling of the working member over the surface in an undulating manner with progressive pressure action.

JOHN W. POULTER.
